UNITED STATES PATENT OFFICE

CHARLES A. FINLEY, OF RUTHERFORD, NEW JERSEY, ASSIGNOR TO BOORUM & PEASE COMPANY, OF NEW YORK, N. Y., A CORPORATION OF NEW YORK

LOOSE LEAF DEVICE

Application filed March 19, 1929. Serial No. 348,237.

This invention relates to loose leaf devices and more particularly to loose leaf ring books. One object of the invention is to produce a structure which is stronger, more rigid, 5 easier to manufacture and having a larger carrying capacity. According to this invention the complementary ring halves are mounted on a pair of braced structures hinged together in place of the ordinary 10 spring-pressed hinge plates.

In the drawings

Fig. 1 is a perspective view of the new binder with the side covers opened out and the ring halves shown in closed position. 15 Fig. 2 is a similar perspective view showing the ring halves and the braced structures carrying same, opened out.

Fig. 3 is an end elevation of the back of the binder with the ring halves in closed 20 position.

Fig. 4 is a sectional view taken on the line 4-4 of Fig. 1 showing the details of the braced structures at one cross-section.

Fig. 5 is a section on the line 5-5 of Fig. 2 25 taken through the ring halves and the braced structures showing a method of mounting ring halves in the braced structures, while

Fig. 6 is a sectional view taken on the line 6-6 of Fig. 1 showing hinged connection 30 between the side covers and the braced structures carrying the ring halves.

One of the commonest types of loose leaf devices is the so-called ring book in which a ring is split into two halves each mounted on 35 a separate plate carrying two or more of such halves, the plates moving the halves or arches apart or together to open or close the book by means of a rising or falling movement of the plates above or below the center line and 40 actuated by the spring pressure of an outer spring plate of C form. The sheets are threaded on the ring halves. When a ring book is made with large rings to give capacity the rings will not stay shut and the 45 plates carrying the ring halves warp and twist the halves open or out of register with each other. In practice it has been found that the C-shaped spring plate and flat ring-supporting members do not function satisfactorily in ring devices of this nature hav-

ing a capacity greater than 1" for the reason that it is impossible to secure enough tension by means of a C-shaped spring plate to hold the half-arches forming the rings, completely closed or in proper alignment. The stronger 55 the C-shaped spring plate is made to overcome this difficulty, the harder it is to open the device in order to remove or insert sheets. According to my invention a braced structure replaces the plain plate and C-shaped outer 60 spring heretofore used.

Referring to the drawings, the ring halves or arches 10, 11 which when closed form an arc greater than 180° on which the sheets are threaded are carried by a binder metal 65 composed of two braced structures or frameworks triangular in cross-section. Each framework comprises a longitudinal plate 12 carrying the ring halves and means bracing the longitudinal edges thereof against 70 lateral or longitudinal warping. These means are at an angle to the plate and are shown as consisting of a vertical leg 13 and a diagonal brace 14. In the drawings the vertical leg 13 is merely a right-angle flange 75 on the inner longitudinal edge of the carrying plate 12 adapted, when the ring book is closed, to lie flush against the corresponding leg of the braced structure carrying the complementary halves of the rings. These legs 80 13 have hinge knuckles 15 thereon threaded on a common pintle 16 (See Fig. 6). Also threaded on this pintle 16 are similar knuckles 17 of the diagonal braces 14. Thus the bracing means form a hinged mounting between the two carrier plates with the hinge line below the plane of the plates. These diagonal braces may, if desired, be curved 85 plates each extending from this main hinge pintle 16 to the outer longitudinal edge of its carrying plate 12 to which edge it is firmly fastened. As shown in Fig. 4 this fastening may consist of a lip 18 passing through the diagonal brace 14 and bent over it on the outside. At the points where these lips 90 18 are located the edges of the braces are formed into hinge knuckles 19. Also in register with these knuckles 19 are knuckles 20 for the side covers 22 and knuckles 21 on the carrying plates 12. I prefer to so locate 100

the lips 18 and the knuckles 19 and 21 of the brace 14 and the plate 12 that the plate 12 is directly fastened to the side pintle 23 on both sides of each ring half either by one of 5 its own hinge knuckles 21 or by a lip 18 and the knuckle 19 of the brace 14. The knuckles 20 of the side cover 22 are formed on plates 24 to which the main cover may be attached in any suitable manner. It will be noted that 10 as a result of this assembly there is a flat writing surface in the binder from edge to edge thereof. In order that the back of the binder may match the side covers, cover pieces 28 may be riveted on the braces 14. 15 In mounting ring halves in ring books it has heretofore been customary to square down, slot or otherwise cut in the wire forming the ring halves in order to mount them in the plates. These ring halves are not only 20 subject to pressure strains not found in other types of binders but are frequently used as handles to spring the book open or shut against the spring pressure heretofore incorporated in ring books. This tends to 25 twist and snap the halves.

My novel means of mounting the ring halves on the carrying plates involves no diminution of the cross-section of the wire and consists in the formation of a shoulder 30 25 around the wire a short distance from the end which is to be fastened to the carrying plate. When the ring half is to be assembled with the carrying plate the end of the wire is inserted through an opening in the 35 carrying plate which is not large enough to permit passage of the shoulder 25. The end of the wire is then hammered down to form a rivet head thus gripping the carrying plate between the shoulder 25 and the rivet head. 40 This gives a larger bearing surface for the wire on the carrying plate forming a stronger connection and one that does not in any way weaken the wire. The length of the bearing surface of the wire on the carrying 45 plate is especially great when the shoulder 25 is formed on the wire in a plane which is not normal to the wire as is the case with the shoulder shown in the drawings. The meeting ends of the complementary ring 50 halves are preferably pointed and notched as shown in Fig. 2.

For the purpose of holding the ring book closed any desired means can be employed which will lock the two braced structures 55 together near the intersection of the carrying plates and the vertical flanges or legs 13. In the drawings I have shown a latch 26 carried on the inside of one of the flanges 13 and projecting through a slot in the flange 13 60 to engage the edge of a corresponding hole in the other flange 13. This latch can be operated from one end of the book by a push rod 27.

It will be observed that the rings can be 65 made of any desired size and that the ring

halves can be thrown open to any desired extent thus permitting the introduction or removal at one time of all the sheets which the binder is capable of holding.

The simplicity and strength of the structure will be obvious. The carrying plates 12 are locked together at their adjacent longitudinal edges and cannot pull apart from each other. They cannot bend or warp downwardly at their outer longitudinal edges because they are braced by the diagonal braces 14. They cannot bend downwardly at their inner longitudinal edges because of the juxtaposed position of vertical flanges 13 and the hinged connection between those flanges. They cannot warp laterally because they grasp the pintles 23 and are braced by the flanges 13. In short, torsion or warping of any kind is impossible owing to the hinge pintles 16 and 23 and the locking action of the vertical flanges 13 and the diagonal braces 14. The uniting of the carrying plates with the pintles 23 on either side of each ring half further strengthens the structure and makes it impossible for the carrying plate to move in any direction. In view of this simple interlocking braced structure the carrying plates form a rigid platform for the ring halves and warping, twisting or springing of the ring halves is eliminated. By these means it is possible to use the same size of wire on a ring book with large rings that is used on a ring book having small rings, and it is, therefore, possible to transfer sheets from a book having small rings to a book having large rings without repunching the sheets.

It will also be observed from Fig. 6 when the book is closed with the side covers open a continuous flat writing surface is provided from one edge of the binder to the other, a feature which is not possible in the ordinary ring book. It will also be observed that side covers are connected in a direct line through the carrying plates and the latch. Modifications which do not depart from the scope of my invention will readily occur to those skilled in the art.

I claim:

1. A loose leaf ring book comprising a pair of carrying plates, complementary ring halves forming an arc greater than 180° mounted on said plates, in combination with rigid means bracing the longitudinal edges of said plates against lateral or longitudinal warping.

2. A loose leaf binder comprising complementary ring halves forming an arc greater than 180°, carrying plates on which said ring halves are mounted, vertical flanges on each of said carrying plates and diagonal braces each reaching from the outer longitudinal edge of the carrying plate to the free edge of the vertical flange, in combination with side covers, and at the adjacent longitudinal edges

of said carrying plates, braces, and side covers, hinge knuckles and pintles uniting same and other hinge knuckles and pintle uniting said braces and vertical flange, rigidly except for hinge motion.

- 5 3. In a loose leaf ring book, a pair of carrying plates, complementary ring halves forming an arc greater than 180° carried by said carrying plates, rigid bracing means hinged together forming a mounting between
10 said two plates, latching means adapted to lock said two plates together to form a rigid platform, each carrying plate being fastened along its outer longitudinal edge to the bracing means on both sides of each ring half by
15 lips and hinge knuckles.

4. A loose leaf binder comprising complementary ring halves forming an arc greater than 180°, carrying-plates on which said ring halves are mounted, vertical flanges on each
20 of said carrying-plates and diagonal braces each reaching from the outer longitudinal edge of the carrying-plate to the free edge of the vertical flange, in combination with hinge knuckles and pintles, uniting rigidly, except
25 for hinge motion, the outer longitudinal edges of said carrying plates and braces, and another pintle and other hinge knuckles uniting rigidly, except for hinge motion, the free edges of the vertical flanges and the inner longitudinal edges of the diagonal braces.
30

In testimony whereof I have signed my name to this specification.

CHARLES A. FINLEY.
